UNITED STATES PATENT OFFICE

LOUIS MARMONIER, OF LYON, FRANCE

METHOD AND APPARATUS FOR DIRECTING TORPEDOES

Application filed September 22, 1927, Serial No. 221,354, and in France September 24, 1926.

My invention relates to an apparatus and a method for the directing and controlling of naval torpedoes and more specifically to the automatic control and submerging of dirigible torpedoes launched from a station either on land or aboard a war vessel. The said invention concerns the type of torpedo control apparatus in which connection is established between the launching post and the 10 torpedo directly by means of a conductor cable placed in the body of the torpedo and paid out proportionately to the speed of the torpedo. The direction and immersion of the torpedo is also controlled by Hertzian waves.

The objects of the invention are, first, to provide an improved method and apparatus for controlling the torpedo by a gyroscopic group of four gyrostats constituting a stabilizing base whose position is invariable in the azimuth and on the horizon; second, to employ naval or land charts for revealing the homothetical positions of the torpedo boat, the enemy ship and the dirigible torpedo at the same time; third, to establish direct connection between the telescopic range finder or range finding periscope and the data of the naval or land charts for verifying the course of the target and of the torpedo; fourth, to provide a method and means for controlling the direction and submerging of the torpedo by control elements which are in turn subjected to the indications on the chart; fifth, to provide a regulating device capable of being controlled from a distance for regulating the gyroscopic control in order that it may correspond with the data of the chart before the torpedo be launched; sixth, to provide means operable from an air-craft for controlling the direction and the plunging of the torpedo by radio control; and seventh, to provide means for automatically supporting the conductor cable connecting the torpedo to the launching post as it is paid out into the water.

My invention is comprised in certain novel forms, construction, and combination of parts, as well as the method of operating said parts in combination, all of which will

hereinafter be fully described and claimed.

In the drawing—

Fig. 1 is an elevational view partly in section of a horizontal naval chart table;

Fig. 2 is an elevational view of the said 55 table associated with a device for connecting it to the periscope of a submarine.

Fig. 3 is a diagram of the automatic tracing device associated with the table;

Fig. 4 is a plan view of the chart table; 60

Fig. 5 is a detail of the disengaging gear of the tracing mechanism;

Fig. 6 is a view in plan of the radio control element;

Figs. 7 and 7^a are illustrative diagrams 65 explaining the operation of the tracing mechanism;

Fig. 8 is an elevational view of a vertical chart table for submarines;

Fig. 9 is a plan view of a horizontal table 70 for the launching post;

Fig. 10 is a diagram illustrating a terrestrial launching post in action;

Fig. 11 is an elevational view of the control board; 75

Fig. 12 and Fig. 12^a are diagrams representing the electrical connections of the control board and the torpedo;

Fig. 13 is an elevational view of the gyroscopic control and the servo-motors associated therewith; 80

Fig. 14 is a view of the vertical and horizontal rudders and their controlling motors;

Fig. 15 is a plan view of a distance controlling mechanism; 85

Fig. 16 is a plan view of a three-contact circuit timer;

Fig. 17 is a sectional detail of Fig. 16;

Fig. 18 is a plan view of the gyroscopic stabilizing mechanism and the control elements associated therewith; 90

Figs. 19, 19^a and 19^b are details of the steering and control rudders and their associated controlling mechanism; 95

Fig. 20 is a detail;

Fig. 21 is a view of the return mechanism of the servo-control motors;

Fig. 22 is a detail of a hydrostatic control piston; 100

Fig. 23 is a detail of the connecting elements of the said piston;

Fig. 24 is a detail thereof;

Fig. 25 is a detail of Fig. 21;

Fig. 26 is a sectional view of the regulating piston;

Fig. 27 is a view of the compensating pump;

Fig. 28 illustrates the way in which the cable is paid out;

Fig. 29 is a section through the torpedo showing the control elements.

The horizontal naval course indicator is illustrated in Fig. 1 and consists principally of a circular frame 1 in which is disposed a transparent sheet 2 of cloth, paper or celluloid. Said sheet which covers the entire surface of the table is stretched over the table by any suitable means such as claw stretchers for example and is renewed after the transcription of each torpedo launching.

The frame 1 (Figs. 1 and 4) is supported by four arms 3, 4 and 5 to which are fastened arms 6, 7 carrying four friction rollers 8, 9 revolving on a circular track 10. The said table 25 normally free to rotate upon track 10 and is adapted to be locked in any desired position by anchor plates 11 and 12 which engage in a groove 16 in track 10 and which are moved to locking position by means of thumb screws 30 13 and 14. The track 10 is disposed on a second track 15 having an inturned flange upon which track 10 turns by means of ball-bearings 17. On the interior of track 15 is fixed a circular toothed plate 18 with which meshes 35 a pinion 19 connected to a worm drive 55 actuated by a motor 20 of special construction which may be connected to the mains of the repeaters of the gyroscopic compass.

Under the action of the repeater motor the course indicator will remain constantly in position in the azimuth.

A socket 21 is fixed to the track 15 by means of arms 22. Fitted in the socket 21 is a supporting tube 23 of a pendulum mass 24. 45 Track 15 is universally suspended by means of a ring 25 pivoted on studs 26 associated with said track and trunnioned at 90° in sockets 27, 28 carried by the frame 29 which serves to support the device.

50 The reproducing mechanism which takes the bearings and traces the evolutions of the torpedo boat of the enemy ship and of the torpedo on the course indicator and which marks their hypothetical positions is shown in Figs. 7 and 7^a.

Two friction discs 55, 56 are driven by bevelled gears 57, 58 respectively.

55 Two driving wheels 59, 60 are adapted to be displaced along the diameter of each of said discs by means of an operating crank 62 pivoted at 63 and two levers 64, 65. In Fig. 7 crank 62 has been moved to the position indicated by the arrow 66.

57 In this position the wheel 60 is moved along the friction disc 56 and occupies the point of

maximum drive thereon, whereas the wheel 59 is disposed in the axis of rotation of disc 55 remains stationary with respect thereto. The respective movements of wheels 59 and 60 are transmitted to the index 76 by means of screw 68, nut 69 and connecting strip 77 for wheel 60 and bevelled gears 70, 71, worm drive 73 and screw 74 for wheel 59. The trace is made on the chart table by means of pointer 76 and it will be readily seen that said trace will have the same direction 66^a as the direction 66 of crank 62.

In Fig. 7^a operating crank 62 has been moved to the position 67 and index 76 will take the direction 67^a as each of the wheels 59 and 60 receives a speed of rotation from discs 55, 56 corresponding to their diametrical position and which is regulated by crank 62. Consequently the speed and direction of travel imparted to pointer 76 on the table is 85 the resultant of the speed of rotation of pinions 57, 58 and the orientation of crank 62.

The device just described is adapted to suit the three subjects of the chart table, to wit, the target, the torpedo boat and the torpedo. 90

This reproducing mechanism is shown in Figs. 1 and 4 and comprises two friction discs 82, 83 which are biased against the driving wheels 88, 89 under constant pressure by means of compressed springs 84, 85 and regulating nuts 86, 87. The discs 82, 83 are actuated by bevelled pinions 78, 79 which in turn are driven by a worm wheel 81 and a worm 80. The wheel 89 transmits its rotation to a threaded rod 90 by means of a reduction gear 91, 92. The screw 90 transmits a motion of translation to a slide block 93 which is adapted to slide throughout the length of a guide strip 94 through the action of a removable half nut 97 which is maintained in a position of engagement or disengagement by means of a spring 98. When said half nut is raised the block 93 can be displaced freely and rapidly along the guide 94. Fastened to the block 93 and extending at right angles thereto is a guide 99 along which moves a guide block 103 controlled by a threaded rod 105 and a removable half nut 104. Screw 105 is given rotation by means of worms 106, shaft 107 and bevelled gears 108, 109. Block 103 is furnished with a small lever 102 trunnioned at 104. Said lever carries a stylus 100 which diagrams the course of the torpedo.

For more accuracy lever 102 might be furnished with two sliding mechanisms disposed at 90° to each other and micrometer screws permitting regulation in all directions on the table if desired. 115

The course of the torpedo is traced as a line on the table in accordance with the orientation of an operating crank 111 and the changing of the bearing of the torpedo becomes a function of the speed of the screw 80. 125

For producing automatically the transcription of the course of the torpedo boat there is 130

provided a toothed ring 112 (Figs. 1 and 3) on the track 15 which is fastened to the frame 29 of the device which in turn is subjected to the evolutions of the torpedo boat. A pinion 113 meshes with said ring and is fixed at the extremity of a shaft 114 journalled in a pair of bearings 117, 118 which are fixed to the chart table and consequently remain in an invariable position.

10 A bevelled gear 115 is fastened on the end of shaft 114 which meshes with a second bevelled gear 116 keyed to a shaft 110 which in turn carries at its extremity a direction control operating crank 186.

15 The said crank takes definitely the positions indicated by the arrow 111 (Fig. 3) which is exactly parallel to the longitudinal axis of the keel of the ship.

20 The gears 112, 116 and the pinions 115, 113 are provided respectively with the same number of teeth so that when the boat changes its course the chart table remains fixed and as a result of the effect of the repeater motor the ship will gravitate about 25 said table and following the inverse movement of gears 112, 113 and 115, 116, the crank 186 will always remain parallel to the arrow 121, 122 whereas its positioning on the table of the chart will always correspond 30 with the change in the course of the ship.

25 The speed of the ship is automatically registered by means of a small exterior windlass which transmits its movement to the worm 80 by means of a flexible coupling 126, Figs. 3 and 4. Said worm actuates the toothed wheel 81 and communicates its rotary movement to the discs 82, 83.

35 The course of the target is traced on the chart table by means of a device similar to that just described with the exception of the distance which separates the target from the torpedo boat as well as its direction and speed. All estimated data is determined by the range officer and is reproduced on the chart table 40 in proportion to the scale thereof.

45 First of all the table is positioned on either the port or starboard side of the ship when the battle is about to be staged. This is accomplished by unscrewing the thumb screws 50 13 and 14 which disengages the anchor places 11 and 12 from the throat 16.

55 The whole table may be turned about the track 10 until the desired position is obtained when it is again locked to track 10.

60 The position chosen should be that in which the line representing the course of the torpedo boat will be to the rear of the line representing the course of the torpedo and the target will be represented at the opposite extremity 65 of the table by the index 150 at a distance 100—150 which is hypothetically that which separates the torpedo boat and the enemy ship to the scale of the chart table.

70 The reproducing mechanism is composed of 75 two friction discs 129, 130 associated with

driving wheels 132, 133 which are positioned by an operating crank 134 and two levers 135, 136. The respective movements of the said driving wheels are transmitted to the pointer 150 by a block 142, a removable half nut 143, a threaded rod 140 and the gear train 137 and transmission of this movement is continued through the wheel 133, bevelled gears 138, 139, shaft 144, worm gears 145, threaded rod 147, removable half nut 149 and block 148.

75 The course of the enemy craft will be reproduced in accordance with the variation of the position of the operating crank 134 and the advance of pointer 150 will be produced in accordance with the regulation of speed of 80 a motor 181.

85 The operator places the range glass on the alidade connecting the index 100 and the index 150. Since index 100 is given automatically a displacement which is a function of the direction and the speed of the torpedo boat, the line of sight AB will cut the enemy ship if the displacement of the index 150 on the table corresponds to the speed and direction of the target. Said range glass 90 could be placed directly on the table if the latter is on a war vessel or torpedo boat and the aim is taken exposed to the fire of the enemy.

95 If it is desired to find the range of the target by means of a periscope in accordance with the data of the table, the alidade 198 connecting the index 100 and index 150 (Fig. 2) will be centralized upon the index 100.

100 A pivotal joint 182 is fixed to a rod 183 which slides in a tube 184 and to which it is feathered by means of a pin 185 thereby permitting the tube 184 to rotate with rod 183. A two contact timer 187 is connected to tube 184 for the purpose of energizing motor 194 through a stationary contact 188. Motor 194 maintains the submarine periscope exactly in the sight line 100—150 of alidade 198 through a worm wheel 192, a worm 193 and bevelled gears 195, 196. Return of the timer to normal position is effected by means of a shaft 191, and bevelled gears 189, 190 which have the same number of teeth as gears 195, 196.

105 The course of the torpedo is traced on the chart table by the pointer 153 (Figs. 1 and 4) which is placed beneath the transparent sheet 2 whereas the pointers 100 and 150 of the torpedo boat and the enemy ship are situated above said sheet. The index 153 can consequently move over the entire surface of the table without interfering with index 100 and index 150.

110 The torpedo tracing mechanism comprises 115 two discs 154, 156 which receive their rotary movement from bevelled gears 155 and actuate the wheels 158, 159. Wheel 159 controls a slide block 165 by means of a removable half nut 166 and a threaded rod 164 which is placed on a diametrical axis of the table. The block 165 is guided by the arm 5 throughout its 120

length and has fixed thereto a guide strip 173 extending to the right and left of said block upon which is adapted to slide the block 174 of pointer 153. Block 174 is attached to a threaded rod 172 by means of a removable half nut 175. Rod 172 receives its motion of rotation by means of transmission gears 171 (Figs. 1 and 4) arbor 170, bevelled gears 178, shaft 169 and bevelled gears 168, 167.

The launching angle of the torpedo is determined by the operator and its course is traced upon the table by an operating crank 160 while the displacement speed of pointer 153, which is proportional to the speed of translation of the torpedo is automatically transcribed by a mechanism about to be disclosed.

If the torpedo is propelled by a motor having its source of energy aboard the torpedo, the speed of translation thereof will be determined by a generator actuated by the propeller shaft which in turn controls the motor of the worm 180 which actuates the discs 156, 154.

On the other hand if the motor of the torpedo is propelled by current from the launching post, the speed of translation of the torpedo varying directly with that of the alternator, the said alternator will be placed in synchronism with the worm 180 and the chart table by means of a flexible coupling (not shown).

The principal organ which directs submerges and stabilizes the torpedo automatically from a remote point and upon which the present system of control is based consists of a gyroscopic group of which the essential feature is the production of a powerful reaction along two planes at right angles to each other and to thus produce a rigid mass on the horizon and in the azimuth.

The present group, shown as an example, and which could be replaced by any device embodying a horizontal and azimuthal lines of faith comprises two gyrostat couples 200, 201 and 202, 203 turning in opposite directions and disposed in planes at right angles to each other, in which position they exercise all of their active force as a result of them being mounted with three degrees of liberty. These gyrostats are universally mounted on a frame 204 disposed in such wise that the mass of the four gyrostats balances on a central pivot 217.

Gyrostat 200 is mounted in a circular support 209 which is pivoted at 210, 211 in a ring 212 which in turn is pivoted at 213, 214 in a bifurcated member 205 fixed to frame 204. The gyrostats are maintained in normal position by means of two springs 215 and four other springs 368 but conserving, however, the aforementioned three degrees of liberty. In this position the azimuthal plane passes by the pivot 217 which is in coincidence with the center of gravity of the whole gyroscopic arrangement.

The above described arrangement is employed for the control of servo-motors which actuate the horizontal rudder 255, the vertical rudder 331 and the lateral stabilizing ailerons 284, 286 which have for a purpose the preservation of a straight course for the torpedo. (See Figs. 19, 19^a and 19^b.)

The frame 204 of the gyroscopic group is mounted on a universal joint 216 disposed on a shaft 206 which is pivoted on a support 207 rigidly secured to the supporting frame 208 of the device. Said frame is placed and rigidly secured in the regulating chamber of the torpedo. As a result all lurching of the torpedo is taken up by the gyroscopic arrangement.

Control of the horizontal rudder is effected by a vertical lever 218 forming a parallelogram with the levers 221, 222. Lever 218 is mounted in a ball and socket joint 219 associated with a circular piece 223. Said circular member is subjected to the frame 104 of the gyroscopes through rollers 220. The arm 222 is keyed to the shaft 224 extending horizontally which carries at its opposite extremity a lever 225 which governs a contact roller 228 of a three point circuit closer 229.

All longitudinal deviation of the torpedo is transmitted to the circuit closer 229 which establishes a circuit between the roller 228 and one of the three contacts 242, 243, 244 (Fig. 20). Each of the said three contacts is connected with one of the hollow electromagnets 230, 231 and 247 having central cores and associated with the horizontal rudder servomotor.

The servo-motors used in this device are of the low pressure (4 to 5 kgs.) compressed air type. They are shown as controlled by electric relays but any other suitable arrangement might be employed which would be readily adapted for use aboard a dirigible torpedo. The radial contact 243 of the three point circuit controller 229 is operatively connected to the electromagnet 247 of the servo-motor brake, the contact 242 with electromagnet 231 and the contact 244 with the electromagnet 230. When the torpedo is in a position of equilibrium contacts 228 and 243 remain closed. This energizes electromagnet 247 and applies the friction brake 260 which blocks the servo-motor. During a lurching of the torpedo roller 228 contacts with one of the contacts 242 or 244 and the corresponding electromagnet 230 or 231 becomes energized and introduces compressed air on one side or the other of piston 248 by actuating air admission and exhaust valves 234, 236 or 239, 240 by means of a pair of double armed levers 232 or 233. The movement of piston 248 is transmitted to a lever 250 through a reciprocating shaft 249 and a cross head 251. In turn the lever 250 operates the horizontal rudder 255, Figs. 13 and 19, through the rods and operating levers 254, 256, 257 and 258.

105
110
115
120
125
130

When the torpedo is restored to a position of equilibrium, the circuit closer 229 is returned towards its original position by a lever 246 and a connecting rod 245 until the circuit is again closed between contacts 228 and 243 at which time the servo-motor is again blocked by the brake 260.

For transverse stabilization of the torpedo, the effect of the gyroscopic group is communicated to the corresponding servo-motor 10 through the vertical lever 261 pivoted to the circular piece 223 by means of a ball and socket joint 264 and is pivotally connected to two arms 262, 263 arranged in parallelogram formation.

Any lurching in the transverse direction of the torpedo will tend to rotate the supporting frame 208 about the arm 263, which through bevelled gears 265, 266 transmits its 20 movement to a transverse shaft 267 carrying a lever 268 at its opposite extremity. Said lever 268 is connected to a contact roller 269 which bears against a three point circuit closer 270 by means of a contact lever 271 25 and a spring 272.

The action of the laterally stabilizing servo-motor is brought about in the same manner as previously described. A pair of electromagnets 274, 275 actuate a piston 278 30 which displaces a connecting rod 281 in one direction or the other according to the compensation which is to be effected. The return of triple circuit closer 270 to its normal position by the servo-motor is obtained by a lever 279 and a connecting rod 280. The operating lever 282 actuated by connecting rod 281 is keyed to a shaft 283 on which is fixed a blade 284 (Fig. 14). Said lever 282 operates a bevelled gear 287 meshing with two bevelled 40 pinions 288 which in turn mesh with a fourth pinion 289 correspondingly bevelled thereby giving pinion 289 a movement in the opposite direction to that of pinion 287 which reverse movement is transmitted to a shaft 285 carrying a blade 286. The torpedo is thus turned about its own axis until equilibrium is re-established transversely.

Compensation takes place entirely automatically and without necessitating the attention of the operator who is then free to 50 occupy himself with the control elements for steering and submerging the torpedo.

The steering of the torpedo is effected by the gyroscopic group through a vertical shaft 290 (Fig. 13) connected to a hollow ended shaft 206 by means of a universal joint 55 507. At the top of shaft 290 is keyed a socket 38 of a plate 37 of the mechanism for controlling the direction from an aircraft.

Pivoted to said mechanism is a lever 291 carrying a roller 293 which revolves on a three point circuit closer 336 carried by a cap 297 (Fig. 16). The contacts carried by 60 65 said cap consist of two semicircular contact

segments 294, 296 and a radially disposed contact 295.

Each of the contacts 294, 296 is connected with one of the electromagnets 324, 325 of the direction servo-motor and the radial contact 295 is connected with the electromagnet 326 of the brake 327 of the servo-motor (Fig. 18). Piston 328 of this servo-motor actuates a connecting rod 330 (Fig. 19^a) and by means of a lever 332 turns the shaft 333 on which is fixed the steering rudder blade 331. The direction servo-motor is returned to its original position by a lever 323, a connecting rod 322 and a lever 321 which is keyed to an arbor 320. Said arbor carries a bevelled gear 319 which meshes with a bevelled gear 318 keyed to a socket 317 of a plate 316. Plate 316 is placed in connection with the cap 297 by means of a special mechanism having for a purpose to permit the operator to steer the 70 75 80 85 90 95 100 105 110 115 120 125 130 torpedo from the launching post.

The mechanism for controlling the vertical rudder from a remote point is composed of two distinct elements one of which turns the cap 297 in the direction of arrow 338 or 90 clockwise and the other of which turns the cap in the direction of arrow 339 or counter clockwise (Fig. 15). Cap 297 turns about a socket 337 of plate 316 and on the inner periphery thereof are provided two sets of ratchet teeth 307, 315. Teeth 307 cooperate with a ratchet 300 one end of which is subjected to the action of a spring 305 which holds the ratchet normally against the teeth 307 while the other end of said ratchet is connected to a core 304 of an electromagnet 303. Ratchet 300 is pivoted at 340 on a lever 301 pivoted on a stud 542 fixed to the plate 316. The electromagnet 303 which controls ratchet 300 is attached to lever 301 and said lever is moved from one side to the other by a spring 306 one end of which is fixed to the plate 316 or by the core 302 of an electromagnet 298 likewise attached to the plate 316.

The mechanism cooperating with the inferior ratchet teeth 315 is similar to that just described and comprises a ratchet 311 pivoted at 342 and moved by the spring 309 or core 312 of magnet 313 attached to a lever 310 turning on a stud 341. Ratchet 311 is carried by one end of lever 310 whereas the other end is adapted to be drawn in one direction or the other by a core 308 of a magnet 299 or by a spring 314. Magnet 299, spring 314 and stud 341 are all carried by plate 316.

The function of this mechanism is as follows:

To change the course of the torpedo the operator places the switch 343 (Figs. 11 and 12) of the control board on the terminal marked "right" if he wishes to direct the torpedo toward the right and closes a circuit between the contacts 362 and 346.

This energizes electromagnet 313 and withdraws the ratchet 311 which up to this time

opposed the rotation of disc 297. By subsequently manipulating the key 347, magnet 298 is energized and attracts lever 301 of ratchet 300 thus moving the disc 297 through a distance of one tooth to the right each time the key 347 is closed.

In like manner if the switch 343 is placed on terminal 344 marked "left" and key 347 manipulated, disc 297 will be stepped around 10 to the left by the opposing mechanism.

Depending upon whether disc 297 is turned to the right or to the left a circuit will be closed between the roller 293 and contact 294 or 296 of circuit closer 336. The direction 15 servo-motor is set into action and moves the vertical rudder which directs the torpedo to the right or left to an amount corresponding to the angular displacement of disk 297.

Since it is essential that the course taken 20 by the torpedo be accurately reproduced by the chart table there is provided a mechanism identical to that utilized for steering the torpedo from a remote point on the control board operated by the operator of the 25 torpedo.

For changing the direction to the right this mechanism comprises a lever 353 supporting an electromagnet 352 and a ratchet 351. Said lever is actuated by an electromagnet 349 30 and an opposing spring 354.

For changing the direction to the left the mechanism consists of a lever 358 supporting an electromagnet 355 and a ratchet 356. Said lever is actuated by an electromagnet 350 35 and a spring 357.

A disc 334 carries the tiller crank pin 359 of the torpedo. This crank pin controls the two driving wheels 358, 359 through levers 161, 162.

40 The position of member 359 represents the direction taken by the torpedo and may be read directly by means of a pointer 360 cooperating with a graduated scale 364.

Consequently the operator of the torpedo 45 may regulate the angular direction of the course of the torpedo to correspond with the position of the enemy craft.

For this purpose disc 334 is adapted to be stepped around to the right or left by the 50 same circuit as that which operated disc 297 and for a distance corresponding to the same number of teeth. Inasmuch as discs 334 and 297 have exactly the same number of teeth, the closing of the key 347 will impart to each 55 of said discs the same angular displacement as represented in the diagram of connections in Fig. 12 and the indication CD on the control board which is placed in view of the operator will be exactly parallel to the course 60 of the torpedo indicated by line EF in Fig. 12^a.

It will be noticed in Fig. 12 that when switch 343 is moved to contact 346 (rightward direction) the magnet 355 of the control board 65 controls the ratchet 356 while at the same

time on the torpedo the magnet 313 actuates the ratchet 311. If at this moment the operator closes the key 347 the electromagnets 349 of the control board and 298 of the torpedo will step around to the same degree 70 and in a clockwise direction the discs 334 and 297 respectively.

Similar operation is produced for directing to the left, the two magnets 350 and 299 75 stepping around together and to the same degree the discs 334 and 297 respectively but in a counter clockwise direction.

The gyroscopic group of four gyrostats utilized in controlling the direction of the torpedo after the gyrostats are released they 80 occupy an invariable position in the azimuth but which may be given any direction whatsoever. Under these conditions the group could not be utilized for directing the torpedo if the operator could not verify the 85 position of the direction of control represented by the contact roller 293, from a distance and before launching the torpedo.

It is therefore very important that the operator be provided with means for verifying 90 the position of the vertical rudder with respect to the gyroscopic control and with respect to the indicators on the control board before him.

Suppose that the lever 291 (Figs. 12^a and 95 16) which carries the contact roller 293 which is connected to the gyroscopic control be placed in the azimuth, after release of the gyrostats, along the line GH (Fig. 12^a) and that the angular adjustment of the course of the torpedo be EF and that the position of the three point circuit closer be IJ, under these conditions it will be readily seen that the direction taken by the torpedo will not be in order upon starting and that control 100 thereof becomes impossible.

For assuring this control the vertical rudder of the torpedo is locked in its position of rest, that is, in a position corresponding exactly to the prolongation of the longitudinal axis of the torpedo. This locking may be effected by any well known means which will 110 be automatically released when the torpedo is released.

The neutral contact 295 of the direction 115 controlling circuit closer which corresponds to the position of rest of the vertical rudder of the torpedo must be reestablished in a position such that line IJ coincides with GH. As this reestablishment cannot be brought 120 about by the operator he must be provided with an indicator which will signal that the roller 293 is in contact with the neutral contact 295. For this purpose the control board (Fig. 11) has been provided with a voltmeter 367 connected to the roller 293 and to the mid point of a battery 368 which in turn has its right and left extremities connected to the contacts 294, 296 (Fig. 12^a). As a result the operator may know at any instant 125 130

with which of the contacts 294, 295 and 296 the contact roller 293 of circuit closer 336 is contacting with. He may then know when to proceed to close the circuit through the 5 neutral contact 295.

This compensation is, however, insufficient as when the circuit is closed between the neutral contact 295 and the roller 293, if the torpedo be launched, it will take the direction 10 corresponding to that which it occupied in the hull of the torpedo boat without concordance with the data on the control board.

With a view to bringing about proper co-ordination the control board has been provided with a pointer 361 which indicates the exact position of the torpedo about to be launched. Said pointer is connected to the torpedo carrier by a mechanism identical to that described in connection with Fig. 3. The 15 said pointer will thus indicate the position of the torpedo on the ship regardless of what evolutions may be performed thereby.

Manual release of the disc 334 is effected by a knob 369 which releases the ratchets 351 20 and 356 by an interior mechanism not shown.

The operator may regulate the course of the torpedo without paying any attention to the evolutions of the torpedo boat other than the release of the torpedo therefrom because 25 as soon as the vertical rudder of the torpedo is free upon release of the torpedo it will take the course indicated by the pointer 360 on scale 364 of the control board.

It will be noted that before launching the 30 torpedo is in the breast of the ship and consequently participates in all its lurching. It will also be noticed that to locate the position of the torpedo on the chart table no bearing is placed thereon. It is even possible to 40 utilize the propelling mechanism of the torpedo for producing the launching thereof which would ordinarily offset the indications on the chart table.

It follows that as long as the torpedo remains 45 on the ship the index 153 which represents the torpedo on the chart table (Fig. 4) will coincide exactly with the index 100 which represents the position of the torpedo boat up to the time of interference and the 50 distance to the scale of the table which separates the torpedo from the table. For this purpose the table has been furnished with transmission mechanisms which transmit the same movement to index 100 and index 153.

Said mechanisms are fastened to lever 376 55 (Fig. 5) and hence associated with rod 377 which displaces a sliding clutch 375 for releasing said mechanisms. Said clutch may be either connected to bevelled gears 373, 372 and 371, 370 whose movement represents the 60 bearings of the torpedo boat or to member 374 whose movement represents the course of the torpedo.

Member 376 transmits the bearings to the 65 chart table. After the launching of the tor-

pedo, that is, at the time the vertical rudder is free and subjected to gyroscopic control, the operator shifts the clutch 375 from member 373 to member 374.

It will be readily recognized by those skilled in the art that once the torpedo is launched, its course will not necessarily be rectilinear and will tend to deviate due to various causes such as the changing tide, submarine currents, waves beneath the surface and the like. It is therefore indispensable 70 that the operator of the torpedo be able to rectify the reproduction of the course on the graphic chart table with respect to the drift produced thereon to which the torpedo is subjected during its travel and of which the direction and extent must be determined.

This drift is reproduced by friction discs 378, 379, a wheel 390 and bevelled gears 380, 381 (Fig. 4). On the diameter of discs 378, 379 75 are placed the wheels 382, 383 which are guided by a drift crank 386 and two levers 384, 385. Here member 386 is not definitely fixed to the extremity of an operating crank as previously but its position is adjustable 80

on a rotary disc 393 (Fig. 11) along a diameter of said disc upon a guide strip 400. Member 386 is mounted in a slide block 392 fitted on guide 400 said block being adapted to be displaced by means of a threaded rod 396 85 and a knob 395. The extent and direction of the drift become a function of the position of member 386 on the disc which is discernible

by a pointer 397 cooperating with a graduated scale 398 and the orientation of member 100 386 in the azimuth which is discernible by means of a pointer 399 cooperating with a graduated circular scale 401 and the speed of motor 389 (Fig. 4) whose speed is adjustable by means of a governing rheostat 402.

The mechanism for indicating the resultant 105 of the normal course of the torpedo and that of the drift will now be described. Referring to Fig. 4, the action of driving wheels 382 and 383 which is dependent upon the position of drift member 386 is transmitted by means of suitable connecting means to the device about to be described which is applicable

equally as well to the longitudinal drift accruing from wheel 382 and arbor 543 as to the transverse drift produced by wheel 383, pinions 386, 387 and arbor 544. Said device 110 is shown in Fig. 5 and comprises a differential gear of which the bevelled gear 407 represents the course of the torpedo (longitudinal and transversal) while the wheel 404 and its worm 403 represent the drift (longitudinal and transversal).

Planet gears 405 of which the stud shafts 115 are fixed to shaft 406 are given a movement of rotation which is the resultant of the rotation either in opposite or the same directions communicated by gears 407 and 404. As a result the shaft 406 reproduces the 120

Planet gears 405 of which the stud shafts 125 are fixed to shaft 406 are given a movement of rotation which is the resultant of the rotation either in opposite or the same directions communicated by gears 407 and 404. As a result the shaft 406 reproduces the 120

course actually run by the torpedo including the effect due to drift.

The verification of the course of the enemy ship and the torpedo by the periscope or range glass in accordance with the indications on the chart table will now be described. The torpedo officer can at one time or other determine by the range officer whether the indications on the table are exact both as concerns the torpedo as well as the enemy craft which might have changed its course or speed.

Said verification is readily determined when the torpedoing takes place on the surface aboard a war vessel or torpedo boat but not so in the case of submarine torpedoing where the torpedo dives as soon as released. Suppose after several minutes the chart table (Fig. 4) shows the position of the submarine at 100°, that of the enemy ship at 150° and that of the torpedo at 153°, an examination of the course will be necessary. The submarine is taken to the surface and the range officer can determine by means of the associated periscope 197 (Fig. 2) whether the enemy ship is still on the line of sight 100°-150°. For this purpose the alidade 198 is placed on the chart table to extend from index 100 representing the submarine to index 150 representing the enemy ship.

The same verification can be made for the torpedo and in this case the torpedo officer places the alidade 198 on the line of sight 100°-150° while at the same time he raises the torpedo to the surface of the sea for several seconds. If at this time some bearing indicating means is brought into action, such as an emergency yard arm, a vertical jet of water, a ray of light in the rear or any other suitable signalling means which will be sufficient to reveal the position of the torpedo to the range officer who has his periscope turned thereon but which means is not readily visible to the enemy, the bearing of the torpedo may be easily taken.

When a torpedo is connected to a wire conducting cable directly connected to the launching post, its density varies in accordance with the unwinding of said conducting cable, placed in the hull of the torpedo at the rear thereof, in proportion to the length of the course of the torpedo.

In order to compensate for this continual loss in weight, there is introduced in the ballast tanks 447 (Fig. 29) of the torpedo a quantity of water whose weight is rigorously equivalent to that paid out in the unwinding cable but at the same time allowing the operator to vary the depth at which the torpedo operates.

The torpedo is furnished for this purpose with a water pump (Fig. 26) which is operated directly from the propeller shaft of the torpedo jointly with the cable unwinding rollers (Fig. 28) carried by the hull of the torpedo. The speed of the pump will be pro-

portional to the length of cable paid out and will charge the ballast tanks with a quantity of water corresponding to the loss in weight. Since the filling of the ballast tanks cannot be rigorously exact, additional elements are provided for regulating the charge. This regulating is accomplished by the joint action of the following elements:

(a) A hydrostatic piston.

(b) The horizontal rudder of the torpedo controlled by the gyroscopic group.

(c) A ballast tank charge regulator.

The hydrostatic piston is of ordinary construction with the difference that its movement is of longer duration in order to receive the least displacement of the torpedo in depth. This device comprises a membrane 422 on a hydrostatic piston 423 mounted in a cylinder 427. Piston 423 is attached to a vertical piston rod 421 which slides in a bearing 428 and carries a trunnion 424 sliding in a slotted lever 425. Said lever is connected to an opposing spring 426 for piston 423, the tension of said spring being regulated from the exterior as is well known in the art.

Rod 421 is provided with an extension 429 beyond the point where it is connected to a depth regulating mechanism about to be described.

During elevation of return lever 245, the servo-motor actuates the horizontal rudder (Figs. 13, 18, 21) and the extension 429 slides vertically in a supporting socket 430 fixed to the torpedo (Fig. 24). The portion of extension 429 in said socket provided with a rack 433 which meshes with a toothed sector 432 extending through said socket and keyed to a shaft 434. The sector 432 consequently registers the ascending and descending movements of the extension 429 fixed to the hydrostatic piston. Fixed to shaft 434 is a universal joint 435 (Figs. 18 and 29) which in turn is attached to a shaft 436 adapted to slide laterally in a sleeve 437 keyed to an arbor 438 which is extended by means of a universal joint 439 and an arbor 442 (Figs. 18, 21 and 25). Shaft 442 is provided with a toothed sector 443 which turns in a socket 444 and meshes with a rack 445 provided on the horizontal rudder return rod 245.

Rod 245 is slidably mounted within the socket 444 while said socket is fixed to extension shaft 245^a of the horizontal rudder return rod.

As a result, if the hydraulic piston is raised due to the submersion of the torpedo being too great, the rod 429 will rotate the toothed sector 432 which in turn will turn in the same proportion the toothed sector 443 through shafts 436, 438. The rotation produced will tend to diminish the effective length of rods 245, 245^a of the horizontal rudder return mechanism. Consequently the contact roller 228 of the gyroscopic control closes the circuit with contact 242 which acts upon the depth

control servo-motor and raises the horizontal rudder 255. The torpedo then moves upward toward the surface until a depth is attained where the hydrostatic piston and the rods 245 and 245^a take their normal position.

5 In case the hydrostatic piston moves downward from the result of a too rapid ascent, the horizontal rudder of the torpedo will be actuated in the reverse direction as indicated 10 to the left of Fig. 21.

During the time that the horizontal rudder tends to make the torpedo plunge or rise, the regulator charging piston 408 (Fig. 26) associated with the ballast tanks acts jointly. 15 Said piston 408 slides in a cylinder 409 surrounded by two chambers 412 and 413, the former chamber receiving water under pressure from an air dome 419 which is fed by a second pump similar to that of Fig. 26 at 420 20 which is used for filling the ballast tanks. The air pressure of dome 419 is maintained at 4 to 5 kilograms above that of the ballast tanks 447 whose pressure is from 6 to 8 kilograms. The pressure in said dome 419 is regulated by means of a spring 417 and an exhaust valve 416 which allows the excess water furnished by the feed pump to escape through a pipe 449.

In the chambers 412 and 413 are furnished 30 openings 411 and 412 respectively which uncover similar openings 410 and 415 oppositely disposed in the regulator piston during reciprocation thereof by rod 429 of the hydrostatic piston. Piping 448 connects the cylinder 409 35 with the ballast tanks 447.

During the normal position of equilibrium of the torpedo the openings 411, 414 and 410, 415 are closed. If the torpedo rises toward the surface as a result of an insufficient charge 40 of water in tanks 447, the hydrostatic piston descends and opens the openings 410, 411 which allows a certain quantity of water to pass from the air dome 419 for compensating for the said insufficient charge.

45 On the other hand if the torpedo plunges too deeply from an excess charge of water, the hydrostatic piston will be raised and open the openings 414, 415 which allows the excess in tanks 447 to escape through pipe 449.

50 The electric transmission device which allows the operator to regulate the depth of the torpedo is the same as that which was described for regulating its direction.

On the control board (Fig. 11) this mechanism 55 comprises an electromagnet 450 and an opposing spring 454 therefore acting on a lever 451 which carries the said magnet 450 and a ratchet 452. Said ratchet cooperates with a toothed sector 461 and turns the same 60 toward the right thereby causing a pointer 463 thereon to move in the direction of the indications on a graduated scale 464 associated therewith. A switch 465 is provided which may be connected to either contact 467 65 for causing the torpedo to rise or to contact

468 for causing it to descend and a key 466 operates the control magnets 450 or 456.

On the torpedo the plunging mechanism corresponding is shown in Fig. 22 and comprises a ratchet 479 actuated by a lever 545 and a magnet 478 while the raising mechanism 70 comprises a ratchet 472 actuated by a magnet 473. The disc formed by the sectors 477, 482 will therefore be moved in a clockwise direction as shown by arrow 546 when plunging and in a counter clockwise direction when ascending. As said disc is connected to an arbor 488 (Figs. 22, 23 and 29) by means of a shaft 483, a universal joint 484, a sleeve 485, a shaft 486 and a universal joint 487; and as 75 the toothed sector 490 is keyed to the arbor 488, rotation of disc 477, 482 in the direction of the arrow 546 will tend to diminish the effective length of rod 421, 489. As a result 80 the horizontal rudder of the torpedo will cause it to plunge as previously indicated and the regulator piston 408 will introduce an overcharge of water in the ballast tanks. 85

Following this shortening of the rod 421, 429 the opposing spring 426 will exert a supplementary tension which must be compensated for by an increased pressure in the water 90 acting on the hydrostatic piston.

Consequently if the torpedo is to recover 95 its equilibrium it must plunge to a depth corresponding to the tension of spring 426 and this plunging will be increased as much as the length of rod 421, 429 is shortened.

On the other hand, lengthening of rod 421, 429 causes the torpedo to ascend toward the 100 surface, this ascending being accomplished through the combined action on the control board (Fig. 11) of ratchet 457, lever 458, magnet 456 and its return spring 460 while on the torpedo through the action of ratchet 472, lever 471, magnet 470 and return spring 474.

A voltmeter 469 is provided for indicating 105 whether the current is flowing properly through the various devices and serves the same purpose for the depth control mechanism as did the voltmeter 367 for the direction controlling mechanism during the running of the course of the torpedo.

The mechanism thus far described has 110 treated solely with the control elements placed at the disposition of the operator at the launching post for permitting the torpedo to be steered and plunged or raised at will. For directional control of the torpedo from an aircraft provided with a transmitter functioning in accordance with a series of variable tuned wave length a receiver placed in the torpedo, the said torpedo will be provided 115 with an antenna, a telemechanical switch and any other necessary radio instrumentalities 120 now in use.

For this purpose the direction controlling 125 servo-motors are provided with a cap 34 of which the interior periphery is provided with 130

two sets of oppositely facing ratchet teeth 35 and 36. On the disc 34 is mounted a lever 291 of a contact roller 293. Said disc is fitted tightly but rotatably on a socket 38 of a plate 37 keyed to the shaft 290 of the gyroscopic group and which serves to support two electromagnets 32 and 33. These magnets control respectively the levers 42 and 43, carrying at their extremities the ratchet 40 and 41 which turn the disc 34 in one direction or the other. The arrangement is completed by opposing springs 44 and 45 (Fig. 6) and return levers 48 and 49 moved by springs 46 and 47 respectively.

15 The intervention of the aircraft will have for a purpose the displacement in an angular direction of the contact roller 293 on the three point circuit closer 294, 295, 296 and consequently to modify the course of the torpedo proportional to said angular displacement.

20 The aircraft must also be able to cause the torpedo to plunge abruptly in order to descend at a great depth beneath the enemy craft when it reaches the target. For this purpose there has been provided (Fig. 29) 25 a radio operated electric depth control means 551 similar to the device 550 which is controlled from the control board. These two devices are actuated upon shortening of the vertical rod 429 of the hydraulic piston and the radio responsive device 551 is connected to the lengthening and shortening mechanism 552 of vertical rod 429 by a universal joint 553.

30 Fig. 8 shows a vertical course indicator particularly adapted for use aboard a submarine where the space available is limited. This device comprises a frame 553 to which is fastened by means of eyelets a sheet of paper 555 gripped between two plates 557 and 559 and stretched by means of tension screws 570.

35 The movement of the submarine is reproduced by means of an index 100 supported by 40 a block 564 slidably mounted in a guide 566 attached to a slide block 562. The longitudinal and vertical movements of translation of index 100 are effected by the threaded rods 561 and 563 which are associated with the direction reproducing operating crank 560.

45 In order that the variations in the course be recorded on the vertical table, the crank 560 is connected with the propelling motor 567 connected to the mains of the gyroscopic repeating motors of the compass of the submarine. The speed of the submarine is transmitted to the data being traced by means of a flexible coupling 565. The bearings of the course taken by the torpedoer is thus automatic as in the table previously described.

50 The course of the enemy craft is traced by the index 150 by means of horizontal and vertical threaded rods 574, 577. A supporting block 575 slides in a guide 576 for rod 574 while a block 579 supports rod 577 and slides

in a guide 578. The course of the target as reproduced is controlled by an indicating pointer 571 associated with the operating crank and the speed by a motor regulating rheostat 573 both within reach of the operator.

55 The torpedo is represented by the index 153 supported by a block 586 sliding vertically in a guide 585 by means of a threaded rod 584 and horizontally in a guide 583 by means of a slide block 582 supporting guide 585 and a threaded rod 581.

60 The control board of this table is similar to that previously disclosed as well as the connections with the torpedo for the submerging and the steering thereof. The depth control is indicated by a pointer 589 on a graduated scale 588. The depth maneuver is controlled by a switch 590 and a key 591 with which is associated a volt-meter 587.

65 The direction of the torpedo is assured by a switch 595 and a key 596 and is indicated by a pointer 592 cooperating with a scale 594 and with which is associated a voltmeter 597.

70 Transcription of the drift is produced by the direction indicating pointer 599 cooperating with a dial 603 and an operating slider 600 regulated by a knob 601 and the extent of the drift is regulated by a rheostat 602.

75 A lever 604 connects the torpedo bearing transmitting mechanism at the time of launching the torpedo.

80 The range of the enemy craft and of the torpedo is found by means of a periscope 605 actuated by a repeater motor 606 and a transmission gear 607. Said motor is connected to the circuit of the alidade of the graphic chart table. Said alidade which is centered on the index 100 which reproduces the torpedoer course, is placed successively from 100^a to 105 100^a for finding the target and from 100^a to 153^a for finding the torpedo.

85 The same arrangement for torpedoing by dirigible torpedoes above described is equally applicable to portable or stationary land launching posts. As the limits of visibility are of wider scope for a post on land, the dimensions of the table will be increased proportionally for obtaining the same precision with a larger launching range. The chart table comprises essentially a frame 491, 492, 493, 494 consisting of four demountable elements assembled by means of bolts (Fig. 9).

90 The course reproducing mechanism is likewise demountable in order to facilitate its transportation by motor truck in the case of portable apparatus. In the frame 491, 492, 493, 494 is placed a sheet 495 of transparent material and demountable which is held in place by adjustable hooks 496.

95 Above said sheet moves the index stylus 520 representing the enemy craft, the trace of which is transcribed on the sheet 495 through the medium of friction discs 497, 498 and driving wheels 499, 500 which are actuated by 100

a motor 512 of variable speed. The longitudinal block 504 and transverse block 506 transmit the course to index 520.

The bearing of the enemy ship and its regulation on the chart table is under control of the range officer who determines the position of the pointer 502 on the dial 501 and the speed by means of rheostat 513 of motor 512. In this end is placed a sight glass 528 pivoted at 533 and which is connected to the alidade extending from the axial point 521 on the table to index 520 of the enemy ship. Said connection is made by means of a rod 530 pivoted at one end at 532 on the prolongation of alidade 520, 521 and at the other end at 531 to a lever 547 keyed to the pivot shaft 533 of sight glass 528.

The sight glass being subjected to the bearings on the chart table with respect to the course of the target the operator can regulate the trace after placing the index 520 at a distance 521—520 which corresponds to the scale of the table, to the exact distance which separates the point 521 from the enemy ship. This distance is reproduced by a telemeter independently.

For the steering and submerging of the torpedo, the operator utilized the same elements of control previously described in connection with the naval chart tables. The control board 511 of the land table comprises a direction control switch for directing the torpedo to the right or left 516 and a key 517; submergence control of the torpedo by a rise and plunge switch 514 and a control key 515; and drift regulation by a movable disc 519 and a speed regulating rheostat 518. Furthermore when torpedoing takes place in the open the operator employs a sight glass 536 for controlling the course of the torpedo from intermittent and rapid observations. Said sight glass is subjected to the course of the torpedo on the chart table which is represented by index 510 by means of the alidade extending from 521 to 510^a. Said alidade which is prolonged to 541 is connected to a lever 538 on the pivotal shaft of glass 536 by means of a rod 540.

The regulation of the gyroscopic control of the torpedo from a distance and its coordination with the movable direction disc of control board 511 takes place in the same manner as previously described. It is merely necessary for the operator of the torpedo to know the direction in which the torpedoes are moored to regulate the position of the movable disc of the chart table as well as the distance which separates point 527 from 524 (Fig. 10) in order that the parallax 521, 522 be represented on the chart exactly to the scale of said chart. The point 522 on the chart table represents the point where the torpedoes are anchored.

This construction of chart table is equally adapted to be utilized in a stationary or port-

able launching post. In the latter case the chart table is transported on a track work by the same auto truck which carries the alternator 526 which furnishes the propelling motor of the torpedo with current (Fig. 10). Said alternator is connected to the chart table for reproducing the speed of the torpedo thereon by means of a flexible coupling 527 and to the torpedo launching relay 529 by means of a conducting cable 528 for furnishing energy to said relay and which cable also carries the transmission wires leading to the direction and submergence control mechanism of the torpedo.

The torpedoes are brought to their mooring place either by water or over the land.

What I claim is:—

1. An apparatus for directing torpedoes comprising, in combination, a chart table, a sheet of transparent material on said chart table, means adapted to reproduce the course of the target on said chart, means adapted to reproduce the course of the torpedo boat on said chart, means adapted to reproduce the course of the torpedo on said chart, a control board associated with said chart and electro-mechanical means for directing said torpedo from said control board.

2. An apparatus for directing torpedoes comprising, in combination, a chart table, a sheet of transparent material on said chart table, automatic means adapted to reproduce the course of the target on said chart, automatic means adapted to reproduce the course of the torpedo boat on said chart, automatic means adapted to reproduce the course of the torpedo beneath the surface of the water on said chart, a control board associated with said chart and electro-mechanical means for directing said torpedo from said control board.

3. The method of controlling a torpedo which comprises utilizing chart tables for reproducing the course thereof, operating said torpedo beneath the surface of water and controlling the evolutions of said torpedo from said chart table, said reproductions and said evolutions being brought about electrically.

4. An apparatus for directing torpedoes comprising, in combination, a chart table, a sheet of transparent material on said chart table, means adapted to reproduce the course of the target on said chart, means adapted to reproduce the course of the torpedo boat on said chart, means adapted to reproduce the course of the torpedo on said chart, each of said means comprising respectively a stylus, a travelling nut for said stylus, a rotatable threaded rod for said travelling nut, a second travelling nut and rod for giving said first travelling nut transverse movement, a plurality of driving wheels, a second plurality of wheels there being one adapted to slide along the diameter of each of said driving wheels, means for varying the position of said

second mentioned wheels with respect to said first mentioned wheels and means for operatively connecting said second mentioned wheels to said threaded rods.

5. An apparatus for directing torpedoes comprising, in combination, a chart table, a sheet of transparent material on said chart table, means associated with a submarine periscope for reproducing the course of the target, automatic means adapted to reproduce the course of the torpedo boat on said chart, automatic means adapted to reproduce the course of the torpedo on said chart regardless of its evolutions and position, a control board associated with said chart and electro-mechanical means for directing said torpedo from said control board.

6. An apparatus for directing torpedoes comprising, in combination, a chart table, a sheet of transparent material on said chart table, means associated with a submarine periscope including a stylus associated with said chart, a contact operated by said stylus and a motor operated by said contact associated with said periscope for obtaining the bearing of the target, automatic means adapted to reproduce the course of the torpedo boat on said chart, automatic means adapted to reproduce the course of the torpedo on said chart, a control board associated therewith and electro-mechanical means for directing said torpedo from said control board.

In witness whereof I have hereunto set my hand.

LOUIS MARMONIER.
